GYRO-MAGNETIC COMPASS

Leslie F. Carter, Leonia, N. J., assignor to Sperry Gyroscope Company, Inc., Brooklyn, N. Y., a corporation of New York

Application December 23, 1938, Serial No. 247,311

5 Claims. (Cl. 74—5)

This invention relates to improvements in direction indicating instruments of the gyroscopic type for airplane use, and especially to the gyro-magnetic compass. Such instruments have been built and used in a variety of forms, but in all of them the necessity of setting the gyroscopic element initially onto the course indicated by the magnetic element requires complicated and sometimes inconvenient additions to the apparatus and occupies too much time of the pilot and his attention while resetting the instrument.

The purpose of this invention is to provide an improved means of causing the gyroscopic element of such instruments to quickly become lined up with the desired heading without precession around its horizontal axis, be it initially when the instrument is started up for the first time or be it during flight, if for some reason or other the instrument has deviated from its correct setting due to drifting or other causes. Such devices have been proposed before, as for instance in my prior copending application for Resetting device for directional gyroscope, now Patent 2,180,221, November 14, 1939. However, it is very difficult to overcome excessive loss of air in such devices, as the clearance between moving parts has to be large enough to prevent mechanical contact, thereby allowing so much air to escape, that the device is only operative in a limited way. This invention improves the resetting device in a novel way and thereby insures reliable functioning without excessive loss of air.

This invention is applicable generally to any direction maintaining gyroscopic instrument, and by way of illustration, I show it as applied to a gyro-magnetic compass, in which the gyroscopic element is controlled in known manner by a magnetic element.

In the drawing,

Fig. 1 shows an elevation section through the housing of a gyro-magnetic compass according to my invention, with certain parts sectioned or partly sectioned.

Fig. 2 shows an enlarged section of a part of Fig. 1 along line I—I.

Fig. 3 is a top view of the resetting knob and the mechanism associated therewith.

Fig. 4 is an enlarged elevation view of part of Fig. 3.

Fig. 5 is a front view of the resetting knob.

The gyro-magnetic compass shown in the drawing is of a type shown in my prior copending application Serial No. 165,667, for Gyro-

magnetic compasses, filed September 25, 1937. It therefore becomes unnecessary to go into a detailed description of the gyro-magnetic compass itself or its principle of operation.

In Fig. 1, the casing 1 is shown in the conventional way as closed by a cover plate 2 having a transparent window 3. Air is exhausted from this casing through pipe 4 in the usual way, the air entering into the casing 1 through a screen 5 in the bottom thereof. The vertical frame 6 of the gyro-magnetic compass is carried on air flow films which are established between the cup members 7 and 8 attached to the casing 1, and spherical members 9 and 10, shaped to closely fit said cups and attached to the vertical frame 6. Another set of similar cups 11 and 12, are carried on the vertical frame 6, and serve, by means of an air film, as bearings for the rotor bearing casing 13 which contains the gyro rotor, the spin axis of which is normally horizontal and perpendicular to the plane of the drawing.

The magnetic element 14 is suspended on the rotor bearing casing 13 and, in known manner, controls the gyroscopic member and its precession by means of air jets and vanes 15, as fully described in my aforementioned copending application. In order to cause the gyroscopic element, which in this case is composed of the gyro rotor, the rotor bearing casing 13 and the vertical frame 6, to precess around the vertical axis at will, or for obtaining adjustment of the card or dial 16 of the instrument, it is necessary to apply a torque to the rotor bearing casing 13 around a horizontal axis normal to the axis of the gyroscope. The horizontal axis around which this torque is applied is therefore located in the plane of the drawing of Fig. 1.

I prefer to apply this torque by means of air jets which can be controlled at will by the operator, and the arrangement of which is shown in Fig. 2. A toothed sector 17 is fastened to the top of the rotor bearing casing 13 in such a way that it is closely adjacent to two apertures 18 and 19 located in the upper spherical member 9 of the vertical frame 6. These apertures are inclined with respect to the vertical so that if air issues from them, the jets would strike the teeth of the sector 17 in a substantially normal direction. During ordinary operation both the apertures 18 and 19 are inoperative, a valve stem 20 shutting off the air supply to the circular recesses 21 and 22 which are connected by passages 23 and 24 to the openings 18 and 19, respectively. The valve stem 20 is hollow at its

lower end and has a number of holes 25 drilled through its cylindrical wall. In the position shown, these holes are closed and the stem is held in its position by means of small balls 26 5 and 27 pressed into a circular recess by means of a spring 28. Another recess 30 is located above the recess and a recess 31 is located below the recess, the distances of these recesses being so arranged that if the valve stem is pulled up 10 until it locks in recess 30, the holes 25 will register with the recess 22. If the valve stem is depressed until the detent snaps into the recess 31, the holes 25 will register with the circular recess 21. A number of slots 33 are milled into 15 the cylindrical wall of the valve stem so that air always can enter into the interior of the valve stem from the air passage 34, which completely surrounds the valve stem.

The top of the valve stem projects into a 20 chamber 60, closed against the atmosphere by a plate 61. As shown in Fig. 4, the stem 20 has a groove 35 into which two pins 37 and 37' (Fig. 3) project. These pins are carried on a fork 38 which is pivoted at 39 in bearing member 40 25 and 41 mounted on the casing 1. The forked member 38 extends beyond the pivot 39 and is slotted at its other end to allow a pin 42 to register therewith. This pin is mounted on a shaft 43 connected to the setting knob 44 located 30 outside of the housing. Three detents 45 are provided in this shaft so that a ball and spring lock mechanism 46 will arrest the shaft 43 in its neutral position and after turning it 90 degrees either way. By turning the knob 44 from 35 its neutral position in a clockwise direction towards the letter "H" engraved on the outer surface of the housing, as shown in Fig. 5, the fork 38 is lifted, thereby lifting the valve stem 20 until it is locked in the upper detent 30 by 40 means of its ball and spring locking mechanism. In this position both the valve stem and the shaft 43 are held in such a way that there is no mechanical contact between them. In this way the detents serve the purpose of separating the 45 fork and the valve stem so that friction cannot develop around the vertical axis of the vertical frame 6, which might otherwise cause precession of the gyroscopic element.

By raising the valve stem to its upper position, 50 air is admitted into the space 22 and will issue from the aperture 18, forming a jet, the energy of which is expanded upon the toothed sector 17, thereby exerting a torque in counter-clockwise direction upon the rotor bearing housing around 55 the horizontal axis of this member. This torque will cause rapid precession of the gyroscopic member around the vertical axis, thereby taking along the dial 16. This precession will continue as long as the valve stem remains in its raised 60 position and will stop immediately as the knob 44 is returned to its neutral position, indicated by "0" as shown in Fig. 5. If the knob 44 is turned in counter-clockwise direction until the pointer 50 registers with the figure "L" in Fig. 65 5, the valve stem is depressed and air is admitted to the passage 21 so that a jet is formed by aperture 19, causing a clockwise torque upon the gyroscopic member. The precession resulting from this torque will be in opposite sense to that 70 described above.

In operation, all the operator has to do to obtain any desired change in the setting of the dial 16 is to turn the knob 44 either clockwise or counter-clockwise, as desired, and to wait until 75 the dial has reached the desired position, at

which point he turns the knob 44 back to its neutral position to stop further precession.

As many changes could be made in the above construction and many apparently widely different embodiments of this invention could be made 5 without departing from the scope thereof, it is intended that all matter contained in the above description or shown in the accompanying drawing shall be interpreted as illustrative and not in a limiting sense. 10

Having described my invention, what I claim and desire to secure by Letters Patent is:

1. In an azimuth indicating free or directional gyroscope having an outer casing, a vertical ring rotatably mounted therein, a compass card fixed 15 to said ring and a rotor bearing frame pivoted in said ring on a horizontal axis; a novel means for resetting said card and ring at will comprising a pair of oppositely directed air jets turnable 20 with said ring, intercepting means on said frame 25 against one or the other of which said jets strike to exert a torque about the horizontal axis of said frame to cause precession in azimuth, a two way valve concentric with the vertical axis for supplying air to said jets, said valve having a 30 stem projecting through said casing into an airtight chamber, means in said chamber operable from without for lowering, centering and raising said valve stem to operate said valve, and separate means for arresting separately said operating means and said valve stem in said three different positions in such a way as to prevent 35 mechanical contact between the former and the latter.

2. In an azimuth indicating free or directional gyroscope having an outer casing, a vertical ring rotatably mounted therein, and a rotor bearing frame pivoted in said ring on a horizontal axis, means for resetting said ring at will comprising 40 a pair of oppositely directed air jets turnable 45 with said ring, intercepting means on said frame against one or the other of which said jets strike to exert a torque about the horizontal axis of said frame to cause precession in azimuth, a three position sliding valve normally closed in its 50 center position and slidably mounted in said ring concentric to its vertical axis and adapted to provide air to one jet in its lower position and to the other jet in its upper position, a stem for said valve for the raising and lowering thereof, and means operable from outside said casing for 55 operating said valve stem.

3. In an air borne directional gyroscope, the combination with the oscillatable rotor bearing casing, rotatable vertical ring and outer casing 55 and air flow bearings between both said casings and said ring including upper and lower buttons on said ring resting on air films in complementary cups in said outer casing, air jets in the under surface of said upper button for exerting 60 torques about the horizontal axis of said bearing casing in either direction, a three position valve means extending through the vertical axis of the upper button for leading air to one or the other of said air jets or shutting off both, and a knob 65 without said outer casing for operating said valve to any of said three positions.

4. In an azimuth indicating free or directional gyroscope having an outer casing, a vertical ring rotatably mounted therein, a compass card fixed 70 to said ring and a rotor bearing frame pivoted in said ring on a horizontal axis; a novel means for resetting said card and ring at will comprising a pair of oppositely directed air jets turnable 75 with said ring, intercepting means on said frame

against one or the other of which said jets strike to exert a torque about the horizontal axis of said frame to cause precession in azimuth, a two way valve concentric with the vertical axis for supplying air to said jets, said valve having a stem projecting through said casing into an airtight chamber, and means in said chamber operable from without for lowering, centering and raising said valve stem to operate said valve.

5 10 5. In an azimuth indicating free or directional gyroscope having an outer casing, a vertical ring rotatably mounted therein and a rotor bearing frame pivoted in said ring on a horizontal axis,

means for resetting said ring comprising a pair of oppositely directed air jets turnable with said ring, intercepting means on said frame against one or the other of which said jets strike to exert a torque about the horizontal axis of said frame 5 to cause precession in azimuth, a three position sliding valve normally closed in its center position and slidably mounted in said ring and adapted to provide air to one jet in one extreme position and to the other jet in its other extreme position, and means for moving the valve to precess the gyroscope in azimuth in either direction.
